HOOP ROLLING PADDLE

Richard J. Kewell, 281 Shepherd Ave. E., Willowdale,
Ontario, Canada

Filed Dec. 2, 1959, Ser. No. 58,530

Term of patent 7 years

(Cl. D34—5)

The lone figure is a perspective view of the hoop rolling paddle showing my new design.

The opposite side of said paddle, not shown, is substantially a mirror image of the side shown.

I claim:

The ornamental design of a hoop rolling paddle, as shown and described.
